CHARLES ROSS, OF BLAIR, NEBRASKA, ASSIGNOR TO BLAIR HORSE COLLAR COMPANY,
OF BLAIR, NEBRASKA.

HORSE-COLLAR.

981,006.

Specification of Letters Patent. Patented Jan. 10, 1911.

Application filed January 5, 1910. Serial No. 526,466.

To all whom it may concern:

Be it known that I, CHARLES ROSS, citizen of the United States of America, residing at Blair, in the county of Washington and State of Nebraska, have invented certain new and useful Improvements in Horse-Collars, of which the following is a specification.

My invention relates to improvements in horse collars of the sweeny type; that is, collars having a full shoulder or draft portion of the after-wale on each side and the top of after-wales reduced in cross-section to produce a slim-topped collar, the fore-wale or rim being of the usual size; and the objects of my improvement are, first, to provide such a sweeny horse collar having a flexible top and throat whereby the side-halves of the same may be adjusted laterally to fit the animal's neck through the medium of the hames and their connecting straps or other couplings; second, to provide strong durable semi-flexible connections or splices to unite the rigid shoulder or draft portion with the flexible sweeny or top and with the flexible throat; and third, to produce in the construction of a horse collar, and conserve in its after service, the qualities of a flexible top or sweeny and a flexible throat, connected by an intermediate, full and rigid draft or shoulder. I attain these objects, with others of minor importance more particularly hereinafter set forth, by the collar structure illustrated in the accompanying drawing, in which—

Figure 1 is a perspective view of the complete collar from a point obliquely forward; Fig. 2, an elevation of the working or shoulder-bearing face of the collar; Fig. 3, a longitudinal section through the after-wale at the broken lines *d* in Figs. 4, 5 and 6; Fig. 4, is a cross-section at the broken line *a* in Figs. 2 and 3; Fig. 5, is a cross-section at the broken line *b* in Figs. 2 and 3; and Fig. 6, is a cross-section at the broken line *c* in Figs. 2 and 3.

Similar numerals refer to similar parts throughout the several views, and the arrow-heads indicate the direction in which the views of the figures referred to are taken at the broken lines.

The rim or fore-wale 5, which is nearly of uniform size and shape in cross-section throughout its length, I prefer to construct with a firm leather outer casing uniformly and compactly filled with a coarse long

fibrous filler 16, as straw, to form a strong but yielding support for all parts of the after-wale. While this fore-wale is made with a coarse long stiff fiber compactly stuffed, being comparatively small in cross-section, it is a sufficiently yielding as well as strong support. The after-wale consists of the face or liner 4 of good firm leather stock continuous throughout the length of the side-halves of the collar. Opposed to said liner, 60 to inclose and form the belly to receive the filling, the top or straight 3 is disposed for the top or sweeny part of the collar; this being in a flexible part of the collar and where there is little wear, for both utility 65 and economy, it is made of a less firm and less expensive piece of leather; and extends downwardly inside the shoulder draft or crook 2 with a wide underlap therein.

The crook 2 at its top end widely overlaps 75 the lower end of the straight, as shown at 17 in Fig. 3, from which lap it extends downwardly its narrow lower end abutting at the center of the throat of the collar a like end of the crook on the opposite half of the collar. These crooks, preferably of selected firm leather stock, have their inner edges with the inner edges of the straights and liners sewed into the closing seam 10 of the rim to secure the whole together. The outer 80 edges of these parts are secured together by the ribbon-thong seam 9 throughout the entire length of the collar halves, said seam bearing inwardly on its course along the sweeny and throat, to reduce these portions 85 as shown, and is supplemented by a thread-stitch closing seam 21 along the immediate outer edge of the collar.

The throat portion of the after-wale is reinforced by the inner throat-facing piece 95 7, and the outer throat-facing piece 6, their inner and outer edges sewn into the seams 10, 9 and 21. Their overlapping ends 19 and 18, like the overlapping top ends 17 of the crooks, are left without any lateral 100 seams or stitching across the wale, so that when the collar is flexed in adjusting, the lapping portions of the splices will slip on each other instead of buckling and wrinkling and perhaps breaking the adjoining 105 integral parts. The wide unsewn laps uniting the firm crooks and pliable straights form flexible splices between these parts, easing the firmness of one into the greater 110 flexibility of the other and vice versa, in-

stead of the abrupt change that would result from seaming these parts together across the wale.

Filling 15 of the throat and 13 of the 5 sweeny, may be of any short or fine fibrous material, as short-cut straw, grain hulls, hair or wool, compacted only sufficiently to leave these parts flexible. But the filling 14 of the drafts or shoulders, is preferably of a 10 coarse long fiber, as straw compacted firmly, like the filling 16 of the rim;—a facing 15 of some fine soft material is usually first placed against the liner as shown in Fig. 5. The top end of this shoulder filling is less 15 compact, being slackly stuffed within the splice 17, and some of the long coarse fibers extended above into the sweeny filling. The filling of the sweeny is incorporated into this slackly stuffed part, intermixed with the 20 upwardly projecting long fibers to form a semi-flexible filling within and adjacent to the flexible splice 17, as indicated at 11 in Figs. 3 and 4. A like splicing of the filling 25 of the throat with the lower end of the shoulder-filling is indicated at 12 in Fig. 3. Thus whole sections of the afterwales, including both the leather casings and the fillings, contribute to form semi-flexible splices connecting the rigid drafts or shoulders of the 30 collar with the flexible sweenys and throat.

A horse collar constructed and shaped as illustrated and herein described can be readily adjusted to the animal's neck and shoulders through the medium of the hames and 35 their top and bottom couplings. It does not break or become distorted at the junctions of its rigid and most flexible parts, and is otherwise serviceable, and comfortable to the creature wearing and working it.

40 I claim:

1. A horse collar, comprising a suitable rim or fore-wale; an after-wale consisting of full length side liners, straights opposed to the top portions of said liners, crooks opposed to the lower portions of said liners and having their top ends overlapped on the lower ends of said straights to form yielding splices without lateral seams or stitching, a closing seam to unite the inner edges of 45 said liners, straights and overlapping crooks with the edges of the casing of said fore-wale, a closing seam to unite the outer edges of said liners to the outer edges of said opposed straights and crooks, a closely compacted filling of long coarse materials between the crooks and liners to form rigid drafts or shoulders, and a less closely compacted finer filling between the straights and liners to form flexible tops or sweenys to 50 said after-wale.

2. A horse collar, comprising a fore-wale, and an after-wale having rigid drafts or shoulders and flexible sweenys or tops con-

nected to said shoulders by flexible splices less flexible than said sweeny or top and 65 also having a flexible throat portion connected by less flexible splices at its ends to the rigid shoulders of opposite sides of said after-wale.

3. A horse collar, comprising a fore-wale 70 having a pliable casing and a substantially uniform filling throughout; an after-wale having full-length pliable side liners abutting at the center of the throat of the collar, pliable tops or straights opposed to the upper 75 portions of said liners, pliable crooks opposed to the lower portions of said liners and having their upper ends overlapped on the outside of said straights without lateral stitching or seams, outer and inner pliable 80 throat-pieces overlapped on the abutted lower ends of opposite side liners and opposite side crooks without lateral stitching or 85 seams, a closing seam to unite the inner edges of said liners, straights, crooks and throat-pieces into the closing seam of said fore-wale, a closing seam to unite the outer edges of said liners, straights, crooks and 90 throat-pieces, a compacted stiff fibrous filling between the liners and the upper parts of said crooks to form rigid drafts or shoulders, finer less compacted filling between the lower parts of said crooks and liners to form a flexible throat portion to said after-wale, and finer less compacted filling between said 95 straights and the upper parts of said liners to form flexible tops to said after-wale.

4. A horse collar, comprising a fore-wale of substantially uniform size and rigidity throughout its length; an after-wale having 100 full-length side liners of firm leather, straights of less firm leather opposed to the top portions of the liners, and also crooks of firm leather opposed to the lower portions of said liners and having their top 105 ends overlapped on the lower ends of said straights to form yielding splices thereto without lateral seams or stitching, draft-fillings of long coarse stiff fibrous materials—as straw—closely compacted between 110 said crooks and liners but less closely compacted at the top ends of said drafts, and top fillings of finer more pliable fibrous materials less closely compacted between said straights and liners, and the lower ends of 115 these fillings inter-compacted with the top ends of the draft fillings to form immediately-pliable splices in the filling athwart the yielding splices of said crooks and straights.

120 In testimony whereof I affix my signature in presence of two witnesses.

CHARLES ROSS.
